(57) **CLAIM**

The ornamental design for a wheel cover, as shown and described.

DESCRIPTION

FIG. 1 is a front perspective view of a wheel cover;
FIG. 2 is a rear perspective view of the wheel cover;
FIG. 3 is a front upper right perspective exploded view of the wheel cover;
FIG. 4 is a front left perspective view of a rear component of the wheel cover;
FIG. 5 is a front elevational view of the rear component of the wheel cover;
FIG. 6 is a rear upper right perspective exploded view of the wheel cover;
FIG. 7 is a rear upper right perspective view of a front component of the wheel cover;
FIG. 8 is a rear elevational view of the front component of the wheel cover;
FIG. 9 is a front elevational view of the wheel cover;
FIG. 10 is a rear elevational view of the wheel cover;
FIG. 11 is a left side elevational view of the wheel cover;
FIG. 12 is a right side elevational view of the wheel cover;
FIG. 13 is a top plan view of the wheel cover; and,
FIG. 14 is a bottom plan view of the wheel cover.

1 Claim, 14 Drawing Sheets
